COIN BANK OR SIMILAR ARTICLE

Irwin Cohn, 746 West St., Leominster, Mass. 01453

Filed Nov. 9, 1970, Ser. No. 25,877

Term of patent 14 years

Int. Cl. D21—01

U.S. Cl. D34—11

FIG. 1 is a front perspective view of a coin bank embodying my view design;

FIG. 2 is a side view thereof showing the side opposite the side shown in FIG. 1;

FIG. 3 is a rear view thereof.

I claim:

The ornamental design for a coin bank or similar article, substantially as shown.
